UNITED STATES PATENT OFFICE.

LOUIS E. ALLYN, OF PEKIN, ILLINOIS.

TANK-CAR.

971,102.

Specification of Letters Patent. Patented Sept. 27, 1910.

Application filed January 22, 1910. Serial No. 539,481.

To all whom it may concern:

Be it known that I, LOUIS E. ALLYN, a citizen of the United States, residing at Pekin, in the county of Tazewell and State 5 of Illinois, have invented certain new and useful Improvements in Tank-Cars, of which the following is a specification.

My invention relates to certain new and useful improvements in tank cars.

10 Referring to the drawings, Figure 1 is a side elevation of a tank and underframe support therefor; Fig. 2 is a detail view showing a section of the underframe and tank and mechanism connecting the tank 15 to the underframe; and Fig. 3 is a detail sectional view of means for supporting, securing and bracing the tank in connection with the underframe; Fig. 4 is a side elevation partly in section of a tank and under- 20 frame showing a modified form of means for attaching and supporting the tank in connection with the underframe; and Fig. 5 is a detail sectional view of a portion of a tank wall, under frame parts and support- 25 ing and connecting means between the tank and the underframe.

Various means have heretofore been employed for securing the tank to the underframe and in all such means with which 30 I am familiar, tank bands and dome rods have been employed, the tank bands to prevent the tank from vertical jumping movement and the dome rods to prevent the tank from circumferential turning upon its sup- 35 port. In addition to the tank bands and dome rods applied for the purpose above indicated, it has been the practice to apply additional means in connection with the tank and underframe to hold it against 40 longitudinal movement.

In my invention I have simplified the means and equipment necessary to perform the several functions enumerated above, thereby reducing the cost of construction 45 and very materially bettering the appearance of the car and in addition thereto have combined very simple means in a relation to very effectually perform the several functions named and very materially better the 50 means.

The object of my invention is to secure the tank upon the underframe in a detachable relation in such a manner as to prevent relative longitudinal movement, to prevent 55 rocking movement and also circumferential movement and in so doing dispense with the

tank bands, dome rods and the commonly used ineffective and cumbersome means for securing the tank against longitudinal movement upon the underframe.

60 In the drawings, 2 refers generally to the tank and 3 to the bottom sheet thereof.

4 refers to commonly used longitudinally extending sills forming a part of the under- 65 frame.

5 is a plate which I have shown herein as formed preferably of cast metal, the upper portion 6 curved to conform with the shape of the tank and provided with flanges 7 adapted to be seated upon the sills 4, as best 70 shown in Fig. 3, the webs 8 being provided to strengthen the flanges.

9 are lugs depending from plate 5 having an open central portion reinforced by web 10, the sides of the lugs being provided with 75 perforations adapted to receive bolts or rods.

11 are clips secured to the underframe in a manner best shown in Fig. 3 and provided with perforated lug portions adapted to receive bolts or rods, as shown in Figs. 2 80 and 3.

12 are rods or bolts adapted to connect the lugs on the plate with the clips on the underframe and to be attached by means of nuts as shown, upon the threaded ends of the 85 bolts or rods. It will be observed that the rods or bolts 12 are disposed angularly, that is, both longitudinally and laterally to brace the tank against rocking and circumferential turning.

90 It will be observed in connection with Fig. 1 that I have applied the plates and connecting means between the plates and the underframe in pairs some distance apart, preferably in practice adapted to be located 95 just inside of the bolsters (not shown) which are universally used on tank cars. This is merely one form of application, but there are many other ways in which it may be applied, as for instance, just one plate may be 100 used and applied at the bottom center of the tank, employing the attaching and bracing rods in exactly the same manner as shown and described, with substantially the same result. Likewise, plates may be attached, one on either side of the bottom center of the tank, as shown in Fig. 4, and secured to the underframe by means of rods and clips in substantially the same manner as illustrated in Figs. 1, 2, 3 and 4. In Fig. 110 4, 20 are plates, adapted to be secured one on each side of the bottom portion of the tank,

as shown in Fig. 5, and which may be provided with flanges as 21 adapted to bear upon the sills 22 of the underframe. These plates are provided with lugs as 23 perforated to receive the rods or bolts 24, which are angularly disposed in the same manner as disclosed in Figs. 1, 2 and 3, and are connected with the underframe by means of clips 25 having perforated lugs 26. The bolts or rods are secured to the plates on the tank and clips on the underframe by means of nuts in the same manner as disclosed in connection with the form of application exemplified in Figs. 1, 2 and 3.

15 What I claim is:

1. In a tank car, the combination with a tank and an underframe support, of means interposed between the underframe and the tank for the tank to rest upon in a relatively detached relation and means for anchoring the tank to the underframe, comprising a plate upon the tank provided with anchor attaching lugs, and a plurality of rods connecting said plate with the underframe, diverging angularly longitudinally and circumferentially with relation to the walls of the tank, whereby the tank is anchored upon the underframe and braced against longitudinal movement, rocking and circumferentially turning.

2. In a tank car, an underframe, a tank, means interposed between the underframe and the tank for supporting the latter in a relatively detached relation upon the underframe, and means for anchoring the tank to the underframe comprising a plate upon the tank provided with anchor attaching lugs thereon, a plurality of anchor rods connecting said lugs with the underframe, diverging angularly longitudinally and circumferentially with relation to the walls of the tank, whereby the tank is anchored upon the underframe and braced against longitudinal movement, rocking and circumferential turning.

3. In a tank car, a tank provided with a plurality of depending anchor members, each diverging angularly longitudinally and circumferentially with relation to the walls of the tank, an underframe comprising a plurality of beams, and means for securing the said anchor members to the underframe, whereby the tank will be held against longitudinal movement, rocking and circumferential turning.

4. In a tank car, a pair of sills, a tank having a casting above said sills provided with anchor lugs thereon, a plurality of rods connected with said casting and diverging angularly longitudinally and circumferentially with relation to the side walls of the tank, and means for detachably connecting said anchor rods to the underframe, whereby the tank is held against longitudinal, rocking and circumferential movement.

5. In a tank car, an underframe, a tank, a plate on said tank overlying the underframe provided with anchor attaching lugs thereon, a plurality of anchor rods connected with the lugs arranged in pairs, each pair diverging therefrom and adapted to be connected with the underframe, and means for attaching said anchor rods to the underframe.

6. In a tank car, a tank, a plurality of anchor rods connected with the tank and diverging angularly longitudinally and circumferentially with relation to the walls of the tank, an underframe, and means for connecting the outer ends of said rods to the underframe.

7. In a tank car, a tank, an underframe, anchor and brace rods connected with the underframe and converging therefrom to a centering point upon the tank and means connecting the rods with the underframe, and the tank.

8. In a tank car, a tank, an underframe, anchor and brace rods connected with the underframe and converging therefrom to a centering point upon the tank and means connecting the rods with the underframe and the tank in a detachable relation.

9. In a tank car, a tank, an underframe, flanged parts secured to the tank and having a bearing and supporting relation with the underframe, and rods connecting the underframe with the tank converging from the former to a centering point upon the latter, to anchor the tank upon the frame and prevent it from rocking or turning.

10. In a tank car, a tank, an underframe including a pair of longitudinally disposed sills, a plate secured to the tank and depending between the sills and provided with an offset to bear upon said sills, and a plurality of rods disposed at angles with reference to the bottom longitudinal length and the circumference of the tank for connecting the plate with the underframe.

11. In a tank car, a tank, an underframe including a pair of longitudinally disposed sills, a plate secured to the tank and depending between the sills and provided with an offset to bear upon said sills, and a plurality of rods disposed at angles with reference to the bottom longitudinal length and the circumference of the tank for connecting the tank with the underframe.

12. In a tank car, a tank, an underframe, a plate secured to the tank and provided with horizontally disposed flanges adapted to rest upon the top of the sills, a plurality of rods disposed at angles relatively with the side walls of the tank and the bottom thereof and connected with the underframe, whereby the tank is seated upon the sills, in a relatively disengaged relation, is connected to the underframe to prevent longitudinal movement upon the frame, and is

braced against rocking and circumferential turning motion.

13. In a tank car, a tank, an underframe, a plate secured to the tank and provided with 5 horizontally disposed flanges adapted to rest upon the top of the sills, and also with a lug, a plurality of rods disposed at angles relatively with the side walls of the tank and the bottom thereof connecting the lugs 10 of the plate and the underframe, whereby the tank is seated upon the sills in a relatively disengaged relation, is connected to the underframe to prevent longitudinal movement upon the underframe and is 15 braced against rocking and circumferential turning motion.

14. In a tank car, a tank, an underframe, a plate attached to the tank having a vertical and lateral bearing relation with the underframe, and brace rods connecting the plate 20 with the underframe and disposed in a relation diverging from the former to the latter.

15. In a tank car, a tank, an underframe including a pair of horizontally disposed 25 sills, a plate secured to the tank and having a vertically and, laterally bearing relation with the sills, a plurality of rods disposed at an angle relatively with the tank and underframe, connecting the former with the 30 latter in a relation to prevent the tank from shifting longitudinally, from rocking and from circumferential turning.

16. In a tank car, a tank, an underframe, a plurality of plates secured to the tank and 25 provided with attachment lugs thereon and each formed with a seat for bearing upon the sills and depending below the sill in a lateral bearing relation therewith, angularly

disposed brace rods connecting the lugs of the plate with the sills in a relation to prevent the tank from longitudinal shift upon the frame and prevent longitudinal rocking and circumferential turning. 40

17. In a tank car, the combination with a tank and an underframe comprising a plurality of longitudinally disposed sills and means for connecting the tank and the underframe in a relation to prevent longitudinal shift of the former upon the latter and to prevent longitudinal rocking and circumferential turning of the tank upon the underframe, comprising a plate secured to the tank and having a vertical and lateral bearing relation with the underframe, and rods or bolts connecting the plate with the underframe, disposed at angles relatively with each other and with the plate and the underframe. 50

18. In a tank car, the combination with a tank and an underframe, including a plurality of longitudinally disposed sills, of a plate attached to the tank, depending between the sills and having a lateral bearing therewith and provided with a seat for vertical bearing relation with the sills, angularly disposed rods connecting the plate 60 with the sills in a relation to prevent the tank from longitudinal shift and to brace it against longitudinal rocking and circumferential turning. 65

In testimony whereof I have affixed my signature in presence of two witnesses.

LOUIS E. ALLYN.
